CLAIM

I claim the ornamental design for a shirt, as shown and described.

DESCRIPTION

FIG. 1 is the front outside view of a first embodiment showing my new design;

FIG. 2 is the front inside view of the shirt shown in FIG. 1;

FIG. 3 is a back inside view of the shirt shown in FIG. 1 with a portion shown in a “dash double dot” circle;

FIG. 4 is a detailed view of the shirt shown in the “dash double dot” circle of FIG. 3;

FIG. 5 shows a back outside view of the shirt; and,

FIG. 6 shows a front outside view of the shirt according to a first embodiment.

The broken lines shown in FIGS. 1 and 6 representing the wording on the outside of the shirt indicate it does not form part of the design.

The broken lines shown in FIGS. 2 and 3 do not form part of the design.
